INVENTOR.

Andrew Wickey,
BY Charles O'Sherry,
his ATTORNEY.

UNITED STATES PATENT OFFICE.

ANDREW WICKEY, OF EAST CHICAGO, INDIANA.

EYEGLASS-GUARD.

1,238,971.

Specification of Letters Patent. Patented Sept. 4, 1917.

Application filed November 13, 1916. Serial No. 130,958.

To all whom it may concern:

Be it known that I, ANDREW WICKEY, a citizen of the United States, and a resident of East Chicago, county of Lake, and State 5 of Indiana, have invented certain new and useful Improvements in Eyeglass-Guards, of which the following is declared to be a full, clear, and exact description.

This invention relates to eye glass guards, 10 and has for its principal object to provide a guard capable of gripping the skin of the nose close to its upper end instead of gripping upon the bony or wider part of the nose. Another object is to provide a simple, 15 substantial and practical guard capable of securely holding the lenses in position in front of the eyes. With these and other objects in view, this invention consists in the several novel features hereinafter described 20 and claimed.

The invention is clearly illustrated in the accompanying drawing, in which:

Figure 1, is a front elevation of a pair of eye glasses embodying a simple form of the 25 present invention, showing the nose gripping end spread apart; Fig. 2, is a plan thereof, showing the nose gripping end in a position occupied when applied to a nose; Fig. 3, is a side elevation of the guard detached from the lenses; Fig. 4, is a vertical section taken on line 4—4 of Fig. 3; and 30 Fig. 5, is a horizontal section taken on line 5—5 of Fig. 3. The views are upon an enlarged scale.

Referring to said drawing, A, B, designate the two lenses between which is the guard C. The lenses are secured to the guard by ears D. An eye glass guard embodying a simple form of my invention 35 comprises two nose piece members 6, 7, pivotally connected together upon a vertical pivot, and a saddle 8, also pivotally connected to the two members 6, 7, on a vertical pivot. Each nose piece member comprises 40 a nose gripping end portion 9, which is concavo-convex in cross section, and formed with a number of small holes to facilitate the holding action. Beyond the nose gripping portion 9, the metal is extended downward to form a side piece 10, which has 45 ears 11, 12, at the top and bottom that are bent at right angles to the side portion 10. The ears 11, 12, of one side portion 10, overlap the ears of the other side portion 50 and are pivotally connected, whereby the

two members 6, 7, may turn upon the common pivot in placing the guard upon the nose or removing it.

The pivotal connection between the ears 11, may be formed by punching down the 60 metal at the center of the ear to form a round lug or boss, 13, which enters a round hole formed in the ear 11, of the other nose gripping member. The pivotal connection between the ears 12, may comprise a screw 65 14, extending through centrally located holes therein. Said screw 14, also pivotally connects the saddle 8, with the nose gripping members.

Projecting from the lower end of each 70 side piece 10, is a finger piece 15, which when the eye glasses are in use extends out over the nose and may be grasped by the user to hold the eye glasses and to place them on the nose or remove them therefrom. 75 Each finger piece is formed with an outwardly pressed bead 16, extending lengthwise of the finger piece, said bead serving to strengthen the material and also to receive one arm of a coiled spring 17, the 80 coils of which encircle the screw 14. The two arms 18, extend out from the coil of the spring and rest in the hollows of the beads 16, wherein they are confined against displacement. If desired, the bead 16, may 85 be extended upward along the middle of each side member to reinforce it.

The saddle has a yoke-like portion 19, which straddles the nose of the user when in place on the nose, and it has a yoke-like 90 member 20, arranged in a plane lying at right angles to the plane of the yoke 19. The two arms of the member 20, straddle the ears 12, and coiled spring 17; and the screw 14, extends through holes in said arms and is 95 threaded in one of them. The cross connecting member 21, of the yoke-like portion 19, is arranged to strike against the adjacent edges of the side members, when the eye glasses have been adjusted to place on a 100 person's nose, and thereby prevent swaying of the lenses upon the pivot between the two side pieces.

The ears D, are secured to the side pieces by screws 22, which pass through the side 105 pieces and are threaded in the base portions of the ears.

To place the eye glasses upon the nose of a wearer, the finger pieces 15, are pressed toward each other against the action of the 110

spring 17, thus spreading apart the nose gripping end portions. This position is seen in Fig. 1; thereupon the nose gripping end portions 9, and yoke member 19, of the saddle placed over the nose with the thin or upper part of the nose between the portions 9. Upon releasing the finger pieces, the spring spreads them apart and consequently crowds the end portions 9 firmly upon the nose and 10 clamps the latter between them, thereby securing the eye glasses in place.

It is to be noted that by reason of this construction of eye glass guard, a bridge or arch piece is dispensed with; that the gripping action is had upon the upper fleshy part only of the nose and not upon the bony portion, whereby uncomfortable pressure is eliminated although the eye glasses remain securely fastened in place.

I am aware that more or less variation of the exact details of construction is possible without departing from the spirit of this invention; I desire, therefore, not to limit myself to the exact form shown and described, but intend in the following claims to point out all of the invention disclosed herein.

I claim as new and desire to secure by Letters Patent:

1. An eye glass guard, comprising two companion lens supporting side members, pivotally secured together, said members being formed at their upper ends with nose gripping end members and being also formed with finger pieces, whereby said side members may be rocked on the pivot, and a spring having arms engaging said finger pieces acting to spread said arms apart and

thereby press together the nose gripping end pieces.

2. An eye glass guard, comprising two companion lens supporting side members pivotally connected together, and formed at their upper ends with nose gripping end portions and at their lower ends with finger pieces, a spring having arms engaging said finger pieces to thereby spread them apart and therewith press together the nose gripping portions, and a saddle pivotally connected with the side members on a pivot coaxial with the pivot of the side members and having a yoke member arranged to straddle the nose of a wearer.

3. An eye glass guard, comprising two companion lens supporting side members, each having top and bottom ears bent at right angles to the plane of the side members, separate pivot connections for the upper ears and lower ears, said side members having at their upper ends nose gripping end portions, and having finger pieces, a spring having two arms pressing against said finger pieces to thereby spread them apart and therewith press together the nose gripping portions, and a saddle carried by the lower pivot member and having a yoke-like member arranged to straddle the nose of a person.

4. A bowless eye glass guard comprising in combination two lens supporting members pivotally secured together, each member being formed with a nose gripping member, and with a finger piece, said nose gripping members being spring-pressed toward each other.

ANDREW WICKEY.
